Carlos L. Page.

CARLOS L. PAGE, OF CAMBRIDGE, MASSACHUSETTS.

Letters Patent No. 88,068, dated March 23, 1869.

IMPROVED MONEY-DRAWER.

The Schedule referred to in these Letters Patent and making part of the same.

To all whom it may concern:

Be it known that I, CARLOS L. PAGE, of Cambridge, in the county of Middlesex, and State of Massachusetts, have invented certain new and useful Improvements in Money-Drawers; and I do hereby declare that the following is a full and exact description thereof, reference being had to the accompanying drawings, and to the letters of reference marked thereon.

The nature of my invention consists in providing a money-drawer with a sliding top, or cover, so arranged that when the drawer is drawn out, the top, or cover comes with it, so its contents are inaccessible; and also so arranged that any person who is behind the counter, and understands the construction of my arrangement, may, by moving a lever, cause the cover to remain stationary when the drawer is drawn out, thus rendering the contents accessible.

To enable others skilled in the art to make and use my invention, I will proceed to describe its construction and use.

In the drawings—

Figure 1 is a perspective view of my drawer as it would appear in a counter.

Figure 2 is a vertical section through the same.

I construct my money-drawer as follows:

D, the drawer proper, is made in the usual manner, of any desired form and size, and is provided with a top, or cover, E, as shown in fig. 2, said cover sliding in grooves, made in the inside of the side-pieces of the drawer.

F O, fig. 2, is a plug, passing up through the bottom of the drawer, and the bracket N, which is attached to the rear end of the drawer D.

This plug is held up by the spring S, so that its upper end passes through the orifice e, in the cover E of the drawer, so that when the drawer D is drawn out, the cover E must come with it, unless the plug F O is lowered so as not to penetrate E.

The plug F O has a notch, near its lower end, into which the end of the lever H projects when the drawer is in, so that any movement of the lever H will cause a corresponding movement of the plug F O.

F' O' is a second plug, attached to the frame of the counter, being operated by the lever H.

The upper end of the plug F' O' fits into an orifice, e', made in E.

The levers F O and F' O', being attached to the opposite ends of the same lever H, they are both operated at the same time; that is, if one is raised, the other is lowered, and *vice versa*.

L is a foot-lever, which, acting through K, operates the lever H, consequently, the two plugs F O and F' O'.

If the plug F' O' is raised, so as to enter the orifice in the cover E, it will hold it stationary, so that if the drawer be pulled out, its contents will be exposed, but if the plug F O be left raised up, as shown in the drawings, the cover E will remain over the drawer, and thus protect its contents.

The action of my invention may be explained thus:

Any one not acquainted with my device would pull out the drawer, without first withdrawing the plug F O and inserting the plug F' O'; hence the cover E would accompany the drawer, and the contents be inaccessible; but a person acquainted with the action of my invention, would first properly adjust the plugs F O and F' O', after which the drawer could be withdrawn without its cover E.

What I claim as my invention, and desire to secure by Letters Patent, is—

The combination and arrangement of the drawer D, cover E, plugs F O and F' O', or their mechanical equivalents, arranged and operating substantially as described and for the purpose set forth.

CARLOS L. PAGE.
